HYDRAULIC ELEVATORS

Joseph H. Borden, Toledo, Ohio, assignor to Toledo Scale Corporation, Toledo, Ohio, a corporation of Ohio

Filed Aug. 12, 1959, Ser. No. 833,203

38 Claims. (Cl. 187—28)

This invention relates to hydraulic elevators.

Hydraulic elevators are particularly well suited for hauling freight and have certain advantages especially for low rise installations. However, heretofore, such elevators have been generally unsatisfactory in certain aspects. Many prior hydraulic elevators have two motor operated pumps each of a different capacity for slow, fast and intermediate speeds, even though it is desirable, from the standpoint of cost, simplicity of operation, and optimum acceleration and deceleration, to operate such a system with only a single motor operated pump and with an infinite number of speeds for any one load for smooth acceleration and deceleration. The prior hydraulic elevators also are unsatisfactory in that they do not provide by simple means a uniform leveling speed and a uniform top or running speed for various loadings. None of the prior hydraulic elevators have a really satisfactory method for leveling the cars at landings. Furthermore, all of the prior hydraulic elevator systems are relatively complicated and bulky.

It is, accordingly, the principal object of this invention to provide an improved hydraulic elevator.

Another object of the invention is to provide a simplified hydraulic control system for an elevator.

A further object of the invention is to provide, for an elevator, a hydraulic system which has an infinite number of speeds for any one load for smooth acceleration and deceleration.

Still another object is to provide, for an elevator, a hydraulic system which has a uniform leveling speed and a uniform top or running speed for various loadings.

Another object is to provide, for an elevator, a hydraulic system having improved means for leveling a car at a landing.

A still further object is to provide, for an elevator, a hydraulic system which is exceedingly compact, easy to operate, of low cost and which is trouble free.

These and other objects and advantages are apparent from the following description of the invention.

According to the invention, the hydraulic elevator includes a single motor operated pump in a line connected to a cylinder having a piston that raises and lowers an elevator car. Two by-passes are provided in the line between the pump and the cylinder and at certain times in the operation they return hydraulic fluid to a reservoir which supplies the pump. A control valve is located in each of the by-passes and each of the valves is provided with a dashpot so that it opens and closes slowly. However, even when fully closed, the valves leak fluid to the reservoir.

Upon the registration of an up start signal, one of the dashpot connected control valves, i.e., the up control valve, which is normally open starts to close slowly and the pump starts an instant thereafter. At this point, perhaps 80% of the hydraulic fluid pumped by the pump is by-passed through the up control valve and returned to the reservoir. There being only 20% of the fluid effec-

2

tive for lifting the elevator car, the car starts up slowly at leveling speed, but accelerates to top speed as the control valve slowly closes. The other by-pass and its dashpot connected control valve, i.e., the down control valve, is isolated from the system during the up travel by means of a fully closed on or off stop valve. As the car approaches the selected landing, the up control valve opens slowly to decelerate the car to leveling speed and when the car is level with the landing the pump is stopped to stop the car. This simple arrangement of a dashpot operated valve in a by-pass provides a smooth acceleration and deceleration in the up direction and in combination with the down control valve together with its by-pass provides a system which is operable with only one pump.

Should the car settle slightly, the pump is started to raise the car at leveling speed—this arrangement being another feature of the system.

Upon the registration of a down start signal, the down control valve which is normally closed starts to open slowly and the stop valve which is in series with the down control valve opens fully. During down travel the pump is not operated. The car starts down slowly at leveling speed under the influence of gravity, but accelerates as the control valve slowly opens. The up control valve together with its by-pass is isolated from the system during the down travel by means of a check valve. As the car approaches the selected landing, the down control valve closes slowly to decelerate the car to leveling speed and when the car is level with the landing the stop valve is closed to stop the car. This simple arrangement of a dashpot operated valve in a by-pass provides a smooth acceleration and deceleration in the down direction.

A further feature resides in the compact design of the valve system which is located as a small unit adjacent the motor operated pump.

Another feature resides in a unique device for automatically operating the up and the down control valves according to the load in the car. This device, there being one for each of the two valves, includes a diaphragm which is sensitive to line pressure and means operated by the diaphragm to control the degree of opening and of closing of the control valve and thus to alter such opening for various loadings to make the leveling and top speeds uniform. Such pressure is a function of the elevator loading, the flow or volume of hydraulic fluid delivered to the cylinder controlling the speed of the elevator car.

A preferred embodiment of the invention is illustrated in the accompanying drawings.

In the drawings:

Fig. I is a diagrammatic representation of a hydraulic elevator embodying the invention;

Fig. II is an elevational view of a subassembly of the hydraulic elevator system with parts broken away and sectioned;

Fig. III is a plan view taken along the line III—III of Fig. II, certain parts being shown in section;

Fig. IV is an elevational view as seen from a position substantially along the line IV—IV of Fig. III, part being shown in vertical section;

Fig. V is an elevational view as seen from a position substantially along the line V—V of Fig. III, part being shown in vertical section;

Fig. VI is an enlarged vertical sectional view of the control valve shown incorporated in the subassembly in Fig. IV; and

Fig. VII is a schematic wiring diagram of an electrical control system for the elevator.

These drawings and the following description illustrate and describe a preferred form of the invention but are not intended to limit its scope.

Referring first to Fig. I, the hydraulic elevator instal-

lation is one in which an elevator car 1, only a fragment of the floor of which is shown, is movable in a hatchway 2 between a floor 3 and another floor located at the level of the car 1 in its position shown. While only operation between two landings will be described for the sake of simplicity, it is to be understood that the elevator may be arranged to serve more than two landings. The elevator car 1 is equipped with hand operated sliding gates or doors and the hatchway 2 is provided with a landing door at each floor; these doors are not shown since they are conventional. However, an example of conventional car doors and a landing door is shown and described in U.S. application Serial No. 671,040, filed on July 10, 1957 in the name of D. L. Baker, wherein the car doors are so operatively and automatically connected to a landing door while the car is at a landing that such doors move together at the landing.

The elevator car 1 is secured to the top of a lifting plunger or piston 4 which extends downwardly into a cylinder 5 through a stuffing box 6. The cylinder 5 is connected to an oil reservoir 7 (Figs. II-V) by means of piping 8, there being a positive displacement pump 9 connected in the piping 8 between the cylinder 5 and the reservoir 7. A motor 10 functions to drive the pump 9 and a pressure wave neutralizing unit 11 connected in the piping 8 adjacent the pump 9 functions to substantially neutralize or eliminate pressure waves which are propagated from the pump. The unit 11 is shown and described in detail in U.S. application Serial No. 709,052, filed on January 15, 1958 in the name of J. H. Borden. The motor 10, pump 9, neutralizing unit 11, and oil reservoir 7, together with various control valving and interconnecting piping hereinafter described, are suitably mounted in a frame 12 as shown in Fig. II in the form of a compact subassembly that can be fabricated in lots at a factory and carried in stock. The pump 9 is connected to the reservoir 7 by means of a conduit 13, a screen 14 in the reservoir straining the oil before it flows by gravity from the reservoir which is under atmospheric pressure to the pump.

The positive displacement pump 9 may be of any desired type but preferably is of the type that is commonly known as a gear pump. The pump when driven by the motor 10 takes oil or another suitable hydraulic medium from the reservoir 7 and forces it through the unit 11 and piping 8 to the hydraulic cylinder 5 which contains the lifting piston 4 that is mechanically connected to the elevator car 1 to be lifted. The hydraulic lifting piston, the elevator car and the connections therebetween may be of any preferred existing type and they therefore are not shown in detail in the drawings.

In the general operation of the elevator, assuming the car 1 is at floor 3, upon the issuance of an up start signal after the doors are closed, the car 1 starts up slowly at leveling speed, accelerates to top speed and continues at top speed until a normally open switch 15 (Fig. I) carried by the elevator car is closed by a stationary cam 16 secured in the hatchway 2 and a normally closed switch 17 which is stationarily mounted in the hatchway is opened by a cam 18 that is carried by the car, the switch 15 being closed just before the switch 17 is opened. The car 1 then starts to decelerate and continues in its upward path until the roller of the normally open switch 15 rolls off of the stationary cam 16. This stops the car. Should the car settle, the switch 15 again is closed, the hydraulic pump is actuated, and the car is moved upwardly at leveling speed to a position level with the second floor. While the car is level with the floor, the switch 17 is held open by the cam 18 as shown in Fig. I.

Upon the issuance of a down start signal, the car starts down slowly under the influence of gravity at leveling speed, accelerates to top speed and continues at top speed until a normally open switch 19 carried by the car is closed by a stationary cam 20 secured in the hatchway 2 and a normally closed switch 21 which is station-

arily mounted in the hatchway is opened by the cam 18 that is carried by the car, the switch 19 being closed just before the switch 21 is opened. The car then starts to decelerate and continues in its downward path until the roller of the normally open switch 19 rolls off of the stationary cam 20. This stops the car. While the car is level with the floor, the switch 21 is held open by the cam 18.

The piping 8 is provided with two return by-passes or conduits each of which includes a manifold 22. The left hand manifold 22 as viewed in Fig. III leads to an up control valve 23 the lower end of which (Fig. IV) opens into the oil reservoir 7 and also leads to a relief valve 24 which is a safety spring valve that is opened by excess pressure in the system to return oil from the piping 8 to the reservoir 7. Normally, the relief valve 24 remains closed. The right hand manifold as viewed in Fig. III leads to an on or off stop valve 25 which communicates with a down control valve 26 the lower end of which (Fig. II) opens into the oil reservoir 7 and also leads to a hand operated valve 27 that functions to run the car down in case of power failure. Opening of the valve 27 permits oil to flow from its lower end (Fig. II) into the reservoir 7. Normally, the valve 27 remains closed. A cover plate 28 on the reservoir keeps the oil therein from splashing or bubbling out, there being tight fitting rings 29 around the valves 23, 24, 26 and 27 that rest on gaskets 30 on the cover plate 28 at the respective openings therethrough. Atmospheric pressure is maintained through an opening 31 in the cover plate 28 at a splash guard 32 (Fig. II) which is supported by the cover plate.

During up travel, the stop valve 25, which is operated as hereinafter described by a solenoid 33 (Fig. VII, line 35 210), is closed to isolate the down control valve 26 from the system. Both of the control valves 23 and 26 are so constructed and operated that they port when in closed position. That is, when the up control valve 23 is fully closed and the pump 9 is operated, as an exemplary figure only, 80% of the total flow at a check valve 34, which is located in the piping 8 between the manifolds 22, passes through the check valve 34 and 20% of the total flow is bypassed through the up control valve 23 to the reservoir. When the up control valve 23 is fully opened and the pump 9 is operated, as an exemplary figure only, 20% of the total flow at the check valve 34 passes through the check valve 34 and 80% of the total flow is diverted through the up control valve 23 to the reservoir.

During down travel, the check valve 34 isolates the up control valve 23 from the system, the elevator car descending under the influence of gravity with the motor-operated pump turned off. Fluid flow is through the then opened solenoid stop valve 25 and the down control valve 26 to the reservoir. When the down control valve 55 26 is fully closed, it allows oil to leak into the reservoir in the same manner as the up control valve does. The control valves are identical except that the down control valve 26 is normally closed while the up control valve 23 is normally open. Hence, during up travel the failure 60 of a solenoid 35 (Fig. IV) which operates the up control valve 23 does not prevent car operation. That is, the normally open up control valve 23 when allowed to open because of solenoid failure only passes about 80% of the total flow at the check valve 34 so that the car will 65 still operate at slow or leveling speed when the up control valve 23 is fully open and when the pump 9 is operating. As in the up direction, the car can descend at leveling speed under the influence of gravity even when a solenoid 36 (Fig. V) which operates the down control valve 26 fails. That is, the normally closed down control valve 26 when allowed to close because of solenoid failure still leaks oil to the reservoir so that the car can descend at leveling speed.

Mechanism for opening and closing the up control valve

23 slowly and for operating the up control valve 23 according to the load in the car is illustrated in Fig. IV. The up control valve 23 includes a valve manifold 37 which communicates with the manifold 22 and that supports a lever pivot post 38 stationarily mounted thereon. An operating lever 39 is pivoted at 40 atop the post 38 and it is attached at its left end as viewed in Fig. IV to the plunger 41 of an oil filled dashpost 42 which is pivotally mounted to compensate for the arcuate movement of the lever by means of a pin 43 on a bracket 44 fixed to the top of the manifold 22, the lever 39 being attached at its right end to a return spring 45 that has its lower end adjustably secured to a stationary bracket 46 carried by the solenoid 35 which is carried in turn on a plate 47 secured to the bottom of the valve manifold 37. A pair of small right angle brackets 48 and 49 is pivotally mounted on the lever 39 by means of pins 50 and 51 as spaced points intermediate the lever pivot 40 and the return spring 45. The armature of the solenoid 35 is operatively connected to bracket 49 by means of a pair of nuts 52 and a valve operating rod 53 is connected to bracket 48 by means of a pair of nuts 54, the brackets 48 and 49 being rockable about the axes of the pins 50 and 51 to compensate for the arcuate motion of the lever 39 to which they are attached. Energization of the solenoid 35 causes the lever 39 to be pivoted in a counterclockwise direction about the pivot 40 as viewed in Fig. IV in opposition to the return spring 45. This lifts the valve operating rod 53, attached to the lever 39, to close the normally open up control valve 23. Upon deenergization of the solenoid 35, the return spring 45 pivots the lever 39 in a clockwise direction about the pivot 40 to reopen the normally open up control valve 23.

The up control valve 23 opens and closes slowly because of the damping effect of the dashpost 42. This provides a smooth acceleration and deceleration on up travel, since the open up control valve 23, i.e., the control valve in its leveling speed position, by-passes perhaps 80% of the total flow at the check valve 34 to the reservoir 7 at the start of the up travel, leaving only 20% of the fluid effective for lifting the car, and closes slowly to produce more and more flow or volume of fluid delivered to the cylinder and thus an infinite number of speeds, whereby a smooth acceleration in the up direction is obtained. The amount of flow of the hydraulic fluid which is devalved to the cylinder controls the speed of the car. Similarly, on approaching the selected floor slow opening of the up control valve 23 leaks more and more oil to the reservoir 7 and the resulting lower and lower flow to the cylinder produces a smooth deceleration until the leveling speed is reached.

The degree of opening and of closing of the up control valve 23 is altered for various loadings through automatically adjustable ranges to make the leveling and running speeds uniform. This is one of the more important features of the elevator system and is accomplished by means of a compensator diaphragm 55 in the form of an oil resisting cylindrical block of flexible material that is so located in the valve manifold 37 that it is contacted along its bottom surface by oil at line pressure. The diaphragm 55, therefore, is sensitive to the pressure in the line which pressure is a function of the loading of the elevator car 1. A compensator guide 56 is stationarily mounted in the valve manifold 37; it has a shoulder 57 and the valve manifold 37 has an abutting surface 58 between which shoulder and surface the diaphragm 55 is held. High line pressure causes the diaphragm 55 to be bowed upwardly in a space 59 above the diaphragm. A cylindrical compensator plunger 60 bears on the top of the cylindrical diaphragm 55 and is concentric therewith; it is slidable in a vertical hole through the guide 56 and it carries a vertical rod 61 that extends through an oversize hole in a stationary spring retaining plate 62 and that is attached by means of nuts 63 to the free end of a compensator lever 64

which is pivoted at its bifurcated end 65 at 66 to the post 38. A compression return spring 67 surrounding the rod 61 is held between a spring seat 68 at its upper end and the upper end of the plunger, the spring seat 68 having an oversize hole through which the rod 61 extends and being forced by the spring 67 against the stationary spring retaining plate 62 that is held in an adjustable position atop a pair of adjustment bolts 69 threaded into the compensator guide 56. Upward movement of the diaphragm 55 is in opposition to the spring 67. The selected positions of the bolts 69 are retained by means of lock nuts 70. The sensitivity of the compensator diaphragm 55 is varied by compressing the spring 67 more or less, i.e., the adjustable force applied by the spring 67 to the diaphragm 55 through the plunger 60 must be overcome by the hydraulic force applied by the oil to the bottom of the diaphragm before the hydraulic force is able to bow the diaphragm upwardly and move the plunger 60 and its attached rod 61 upwardly.

20 The valve operating rod 53 extends through a hole 71 in the compensator lever 64 and carries on either side of the hole 71 a pair of stop nuts 72 which when they contact the lever 64 limit the amount the up control valve 23 can be opened or closed. Since the position of the lever 64 is determined by the hydraulic pressure upon the diaphragm 55 to which it is operatively connected, i.e., movement of the diaphragm pivots the lever 64 about its pivot 66, when the nuts 72 contact the lever 64 they limit the amount the up control valve 23 can be opened or closed according to the line pressure and, hence, according to the loading of the car 1. Energization of the solenoid 35 causes the lever 39 to be pivoted in a counterclockwise direction as viewed in Fig. IV about the pivot 40 in opposition to the return spring 45 until the lower pair of the nuts 72 on the valve operating rod 53 connected to the lever 39 contact the bottom of the compensator lever 64. This closes the normally open up control valve 23 to an extent that is a function of the car loading. Upon deenergization of the solenoid 35, the return spring 45 pivots the lever 39 in a clockwise direction about the pivot 40 until the upper pair of the nuts 72 contact the top of the compensator lever 64. This opens the normally open up control valve 23 to an extent that is a function of the car loading. The net result is an operation of the up control valve 23 in accordance with various loadings to make the leveling and running speeds uniform.

50 The up control valve 23 is shown in enlarged detail in Fig. VI; it includes a cylindrical valve casing 73 having an upper threaded end 74 which is received in the bottom of the valve manifold 37 to communicate therewith and a ring 75 welded in an oil-tight manner on its lower end. A cylindrical valve sleeve 76 that has a horizontal row of equally spaced round holes 77 and a horizontal row, below the row of round holes 77, of equally spaced triangular holes 78 is stationarily mounted concentrically within the casing 73 by means of a strap 79 that is secured to the ring 75 and upon which the valve sleeve 76 bears. The valve sleeve 76 extends through the ring and fits therein with a tight fit to prevent leakage of oil. An elongated valve guide 80 having a foot 81 is stationarily mounted atop the valve sleeve 76 in oil sealed relationship by means of screws 82 and extends from its foot 81 through the casing 73 and through the valve manifold 37 in the form of a sleeve and is held against movement transverse to its axis by means of a tight ring 83 atop the valve manifold 37.

55 The valve operating rod 53 is located within the sleeve-like valve guide 80 and it is secured at its lower end to the top of a valve insert 84 which is slidably mounted within the sleeve 76. The valve insert 84 is provided with a relatively wide and deep circumferential groove 85, a vertical hole 86 along its axis, and three equally spaced holes 87 which lead from the top of the valve insert at an angle into the hole 86, the holes 87 functioning as

bleed passages that carry any oil which leaks past the valve insert 84 to the vertical hole 86 in which it runs to the reservoir 7. Flow of oil is through the round holes 77 in the valve sleeve 76 into the circumferential groove 85 in the valve insert 84 and out of the triangular holes 78 in the valve sleeve 76 and down into the reservoir 7, the pressure within the casing 73 being at line pressure and the pressure at the triangular holes 78 in the reservoir being at atmospheric pressure. As shown in Fig. VI, all of the triangular holes 78 are covered by the valve insert 84 except for a small portion at the apex of each triangle. This is the closed position of the valve, i.e., even when closed the valve leaks oil to the reservoir. Slight downward movement of the valve insert 84 from its position shown in Fig. VI has its effect magnified by the fact that the areas of the triangular holes that are exposed to oil flow increase rapidly in a direction downward from the apex. Similarly, slight upward movement of the valve insert 84 has its effect magnified. Hence, the valve is quite sensitive to any change in the range limits within which it operates, i.e., the limits set automatically by means of the pressure sensitive compensator diaphragm 55.

It was found that a relatively large solenoid 35 was required to operate the up control valve 23 insofar as it has been described. This was discovered to result from a pressure reduction at 88 in the valve insert 84 due to oil flow through the triangular holes 78. Hence, line pressure at 89 within the valve insert 84 overbalanced the reduced pressure at 88. This pressure difference had to be overcome by the solenoid. The system is never static because the triangular holes 78 are never completely closed. If they were, then the force at 88 in a downward vertical direction would exactly balance the force at 89 in the upward vertical direction because line pressure would be imposed on each of these equal areas. The unbalance of forces due to the pressure drop induced by fluid flow across surface 88 is compensated for in the up control valve 23 by means of a pin 90 which has an upper surface 91 and that is arranged to slide in an opening through the foot 81 of the valve guide 80 and through an opening in a collar 92 that is stationarily mounted on the valve guide 80 as a guide for the pin 90. A stop 93 on the guide 80 limits upward travel of the pin 90. The pin 90 bears upon a spacer 94 that bears in turn upon the upper end of the valve insert 84 which is held in place by means of the valve operating rod 53 that passes through an opening in the spacer 94. Force on the upper surface 91 of the pin 90 adds to the downward force applied at 88 to the valve insert 84 and so tends toward a balance of the forces in all directions on the valve insert 84 that the valve can be operated in either direction with relatively little effort. Hence, the solenoid 35 can be of relatively small size.

The control valves are identical except that the down control valve 26 is normally closed while the up control valve 23 is normally open. Reference numbers in Figs. II and V which are applied to the down control valve 26 and which are similar to those applied to the up control valve 23 identify similar parts. Mechanism for opening and closing the down control valve 26 slowly and for operating the down control valve 26 according to the load in the car is illustrated in Fig. V. The down control valve 26 includes a valve manifold 95 which communicates with the stop valve 25 and that supports a lever pivot post 96 stationarily mounted thereon. An operating lever 97 is pivoted at 98 atop the post 96 and it is attached intermediate its ends to the plunger 99 of an oil filled dashpot 100 which is pivotally mounted to compensate for the arcuate movement of the lever by means of a pin 101 on a bracket 102 secured to the top of the right hand end, as viewed in Fig. V, of a bracket 103 which is secured in turn to the solenoid 36. A bracket 104 on the lever 97 serves to join the lever to

the top of the plunger 99. The solenoid 36 is carried by a recumbent L-shaped bracket 105 which is fixed to the valve manifold 95. The lever 97 is attached at its left end to a return spring 106 that has its lower end 5 adjustably secured to the bracket 103 on the solenoid 36.

A pair of small right angle brackets 107 and 108 is pivotally mounted on the lever 97 by means of pins 109 and 110, the angle bracket 107 being located at 10 the right end of the lever and the angle bracket 108 being located intermediate the return spring 106 and the dashpot 100. The armature of the solenoid 36 is operatively connected to bracket 108 by means of a pair of 15 nuts 111 and the valve operating rod 53a is connected to bracket 107 by means of a pair of nuts 112, the brackets 107 and 108 being rockable about the axes of the pins 109 and 110 to compensate for the arcuate motion of the lever 97 to which they are attached. Energization of the solenoid 36 causes the lever 97 to be 20 pivoted in a clockwise direction about the pivot 98 as viewed in Fig. V in opposition to the return spring 106. This lowers the valve operating rod 53a, attached to the right end of the lever 97, to open the normally closed down control valve 26. Upon deenergization of the 25 solenoid 36, the return spring 106 pivots the lever 97 in a counterclockwise direction about the pivot 98 to reclose the normally closed down control valve 26.

The down control valve 26 opens and closes slowly 30 because of the damping effect of the dashpot 100. This provides a smooth acceleration and deceleration on down travel in the same manner as the dashpot 42 (Fig. IV) produces smooth acceleration and deceleration on up travel as hereinbefore described.

The degree of opening and of closing of the down 35 control valve 26 is altered for various loadings in the same way that the degree of opening and of closing of the up control valve 23 is altered as hereinbefore described. Reference numbers in Fig. V which are applied to the mechanism for operating the down control valve 40 26 according to the load in the car and which are similar to those applied to identical mechanism shown in Fig. IV identify like parts.

With reference to Fig. VII, relays and all other circuit elements are shown in an across-the-line diagram. 45 The relay contacts therefore are often located remote from their actuating coils. In order to correlate the location of the actuating coils and contacts, a marginal key has been employed with the circuit diagram. With this key, the diagram has been divided into horizontal 50 bands which are identified with line numbers in the right hand margin. Relay symbols are located in the margin to the right of the line numerals and in horizontal alignment with the coil positions. The location of each contact actuated by a relay coil is set forth to the right of 55 the relay symbol in the key by the numeral of the line upon which it appears. The numerals designating the location of back contacts, those which are normally closed when the relay is de-energized and are open when it is energized, are underlined in the key to distinguish them from front contacts, those which are closed upon their actuating coil being energized. Thus, the time relay ULT appearing in line 212 has a front contact at line 200 and a back contact at line 202 as signified by the numerals in the margin of Fig. VII at line 212.

60 An operator for example, who wishes to go to the second floor enters the car at the first floor and closes the car gate or door by hand, the car gate being so operatively connected to the hall doors that the hall doors also close as hereinbefore described and operates a push button 113 in line 216. Cams (not shown) carried by the gate and hall doors mechanically close normally open switches 114 and 115 in a supply lead 116. Current then flows from the supply lead 116 through the push button 113, the energizing coil of a sealing relay S in line 216, 65 the normally closed switch 17 in line 216 which is in the

hatchway and which is held open by means of the cam 18 on the car while the car is level with the second floor, as shown in Fig. I, the energizing coil of an up relay U in line 216, and down relay contacts D in line 216 to a return lead 120. The sealing relay S in line 216 thereupon closes its contacts S in line 215 to provide a sealing circuit around the push button 113 and the up relay U in line 216 closes its contacts U in lines 219, 207, and 204, and opens its contacts U in lines 218, 205 and 210.

The opening of the up relay contacts U in line 218 insures that the energizing coil of a down relay D in line 218 cannot be energized accidentally at this time. The closing of the up relay contacts U in line 207 permits rectified current to flow to the coil of the up control valve solenoid 35 in line 207 (also see Fig. IV) and the normally open, dash-pot damped up control valve 23 starts to close. The opening of the up relay contacts U in line 205 cuts off current flow to the energizing coil of a time relay DT in line 205 which was energized by current flow from the supply lead 116 upon the closing of switches 114 and 115. Deenergization of the time relay DT causes its normally closed contacts DT in line 204 to close after a brief delay, i.e., the time relay has a slow drop out. Current then flows through the now closed time relay contacts DT in line 204 and the now closed up relay contacts U in line 204 to the motor 10 in line 203 (also see Fig. II). This starts the pump 9. The delay caused by the slow drop out of the time relay DT in line 205 allows the up control valve 23 to start to close before the motor 10 starts.

The closing of up relay contacts U in line 219 permits current to flow to the energizing coil of an auxiliary up relay U1 in line 219. The energization of the auxiliary up relay U1 in line 219 causes it to close its contacts U1 in lines 212 and 213. The closing of auxiliary up relay contacts U1 in line 213 completes a circuit to the energizing coil of a retiring cam relay RS in line 213 and the closing of auxiliary up relay contacts U1 in line 212 completes a circuit to the energizing coil of a time relay ULT in line 212. Energization of the retiring cam relay RC in line 213 causes its contacts RC in line 201 to open and the energization of the time relay ULT in line 212 causes its contacts ULT in line 200 to close and its contacts ULT in line 202 to open.

The elevator car starts to move upwardly as soon as the motor starts at an increasing speed with a smooth acceleration until the up control valve 23 is fully closed and thus full speed is reached. As the car approaches the second floor, the normally open switch 15 in line 201 (see also Fig. I) on the car is closed mechanically by the stationary cam 16 in the hatchway and shortly thereafter the normally closed switch 17 in line 216 in the hatchway is opened by means of the cam 18 on the car. The closing of switch 15 in line 201 completes a circuit to the energizing coil of a leveling up relay LU in line 201, current flowing through such coil and through time relay contacts ULT in line 200. Energization of the coil of the leveling up relay LU in line 201 causes it to close its contacts LU in line 203 which completes a second circuit to the motor 10, the first circuit to the motor 10 being through the lead at line 204.

The opening of switch 17 in line 216 opens the circuit to the up relay U in line 216 and its contacts U in lines 219, 218, 207, 205, 204 and 210 return to their original positions, i.e., their positions shown in Fig. VII. The opening of up relay contacts U in line 207 breaks the circuit to the up control valve solenoid 35 in line 207 and the normally open up control valve 23 starts to open slowly and, therefore, the elevator car starts to slow down with a smooth deceleration. The opening of up relay contacts U in line 204 breaks the first circuit to the motor 10, the motor still being energized through the circuit at line 203. When the car is level with the second floor normally open switch 15 in line 201 opens breaking

the circuit to the leveling up relay LU in line 201 and its contacts LU in line 203 open breaking the second circuit to the motor 10 and the car stops. In the up direction, there is no overrun of the car even with a light load, the car being operated at slow or leveling speed just before it stops.

While the car is level with the second floor, switch 17 in line 216 continues to be held open as illustrated in Fig. I. Should the car settle slightly switch 15 in line 10 201 is closed again but switch 17 in line 216 continues to be held open to complete the circuit to the leveling up relay LU in line 201 which then closes its contacts LU in line 203 to start the motor 10. This causes the car to be moved upward at slow or leveling speed because 15 at this point up control valve solenoid 35 in line 207 is deenergized and the normally open up control valve 23 is fully open. When the car again is level with the 20 second floor, the normally open switch 15 in line 201 opens breaking the circuit to the leveling up relay LU in line 201 and its contacts LU in line 203 open breaking the circuit to the motor 10 and the car stops level with the floor.

As the car approached the second floor, i.e., before the leveling up operation, the closing of switch 15 in line 25 201 completed a circuit to the energization coil of the leveling up relay LU in line 201, the current flowing through such coil and through the time relay contacts ULT in line 200. However, in the leveling up operation, the time relay contacts ULT in line 200 are open, since 30 switch 17 in line 216 is held open at this time opening the circuit to the up relay U in line 216 the deenergization of which, by the opening of its contacts U in line 219, causes the deenergization of the auxiliary up relay U1 in line 219 the deenergization of which, by the opening 35 of its contacts U1 in line 212, causes the deenergization of the time relay ULT in line 212 permitting the opening of the time relay contacts ULT in line 200. During the leveling up operation, however, the retiring cam contacts RC in line 201 are closed, since the retiring cam relay 40 RC in line 213 is deenergized by the opening of the auxiliary up relay contacts U1 in line 213, and when the closing of switch 15 in line 201 completes a circuit to the energization coil of the leveling up relay LU in line 201 current flows through such coil and through the retiring cam contacts RC in line 201 to the return lead 120. 45 Deenergization of the time relay ULT in line 212 causes its normally open contacts ULT in line 200 and its normally closed contacts ULT in line 202 to open and close, respectively, after a brief delay, i.e., the time relay has 50 a slow drop out. The delayed opening of the time relay contacts ULT in line 200 assures an unbroken circuit to the motor 10 at this time so that there is no discontinuity in motor operation before the retiring cam contacts RC in line 201 drop in while stopping on the up trip.

While only operation between two landings has been described, it is to be understood that the elevator may be arranged to serve more than two landings.

To start down, a push button 141 in line 218 is operated. When gate and door contacts 114 and 115 are closed, current then flows from the supply lead 116 through the push button 141, the energizing coil of a sealing relay S1 in line 218, normally closed switch 21 in line 218 which is in the hatchway and which is held 60 open by means of the cam 18 on the car while the car is level with the first floor, the energizing coil of the down relay D in line 218, and the up relay contacts U in line 218 to the return lead 120. The sealing relay S1 in line 218 thereupon closes its contacts S1 in line 217 65 to provide a sealing circuit around the push button 141 and the down relay D in line 218 opens its contacts D in line 216 and closes its contacts D in lines 214, 210 and 208, respectively.

The opening of the down relay contacts D in line 70 75 216 insures that the energizing coil of the up relay U in line

216 cannot be energized accidentally at this time. The closing of the down relay contacts D in line 210 completes a circuit to the coil of the stop valve solenoid 33 in line 210 whereupon the stop valve 25 (Fig. III) opens. At the same time, the closing of the down valve contacts D in line 208 permits rectified current to flow to the coil of the down control valve solenoid 36 in line 208 and the normally-closed, dashpot-damped down control valve 26 starts to open. The closing of the down valve contacts D in line 214 completes a circuit to the retiring cam relay RC in line 213 which opens its contacts RC in line 201.

The elevator car starts to move down under the influence of gravity as soon as the stop valve 25 is opened at slow or leveling speed and, as the down control valve 26 opens, at an increasing speed until full or running speed is reached. As the car approaches the first floor, the normally open switch 19 in line 202 on the car is closed mechanically by the stationary cam 20 in the hatchway and shortly thereafter the normally closed switch 21 in line 218 in the hatchway is opened by means of the cam 18 on the car. The closing of switch 19 in line 202 conditions a circuit to be completed to the energization coil of a leveling down relay LD in line 202 as soon as the retiring cam contacts RC in line 201 close. The opening of switch 21 in line 218 breaks the circuit to the down relay D in line 218 and its contacts D in lines 216, 214, 210 and 208 return to their original positions, i.e., their positions shown in Fig. VII. The opening of the down relay contacts D in line 208 opens the circuit to the coil of the down control valve solenoid 36 in line 208 and the normally closed down control valve 26 starts to close slowly. This causes a reduction in the speed of the car to the slow or leveling speed. At the same time, the opening of the down relay contacts D in line 214 breaks the circuit to the retiring cam relay RC in line 213 and its normally closed contacts RC in line 201 close to complete the circuit through the closed switch 19 in line 202, the coil of the leveling down relay LD in line 202, the time relay contacts ULT in line 202, and through the retiring cam contacts RC in line 210. Energization of the coil of the leveling down relay LD in line 202 causes it to close its contacts LD in line 211 to keep a circuit to the stop valve solenoid 33 closed even though the down relay contacts D in line 210 are now open. When the car is level with the first floor, normally open switch 19 in line 202 opens breaking the circuit to the leveling down relay LD in line 202 and its contacts LD in line 211 open breaking the circuit to the stop valve solenoid 33. The stop valve 25 closes and thus the car is stopped level with the first floor.

It may be desirable under some circumstances to control the system by means of a single compensated control valve. Such a system includes, with reference to Fig. III, the motor-operated pump 9, the normally open control valve 23 in its by-pass to the reservoir, the check valve 34 and the cylinder 5, i.e., the manifold 22 for the stop valve 25, the stop valve 25 and the control valve 26 are eliminated from the system. In place of such manifold 22, the stop valve 25 and the control valve 26, a conduit from the cylinder to the control valve 23 is provided to by-pass the check valve 34, there being a solenoid operated on or off valve in the conduit. Alternatively, such manifold 22, the stop valve 25 and the control valve 26 are eliminated and a solenoid operated check valve which can be opened to permit flow of hydraulic medium from the cylinder to the control valve 23 is substituted for the ordinary check valve 34.

To start up, the motor-operated pump is started and the normally open control valve 23 which is open prior to the start up is closed slowly to produce the acceleration, the check valve 34 and the solenoid operated on and off valve in the conduit which by-passes the check valve 34 or in the alternative arrangement the solenoid operated check valve which is substituted for the ordinary

check valve 34 preventing backward flow of hydraulic medium from the cylinder to the control valve 23. To stop on up travel, the now closed control valve 23 is opened slowly to produce the deceleration and the elevator car is stopped by stopping the motor-operated pump 9.

To start down, the motor-operated pump is kept stopped and the normally open control valve 23 which is held closed prior to the start down opens slowly to produce the acceleration, the flow of hydraulic medium being from the cylinder 5 through the solenoid operated on and off valve in the bypass around the check valve to the control valve 23 or in the alternative arrangement through the solenoid operated check valve which is substituted for the ordinary check valve 34 to the control valve 23. To stop on down travel, the now open control valve 23 is closed slowly to produce the deceleration and the elevator car is stopped by closing the solenoid operated on and off valve in the bypass around the check valve or in the alternative arrangement by closing the solenoid operated check valve which is substituted for the ordinary check valve 34 to stop all flow of hydraulic medium from the cylinder to the control valve 23.

It is to be understood that the foregoing detailed description is given merely by way of illustration and that many variations may be made therein without departing from the spirit of the invention.

Having described the invention, I claim:

1. In a hydraulic elevator system, in combination, a hydraulic cylinder, a reservoir containing a hydraulic medium, conduit means connecting the cylinder and the reservoir, pumping mechanism in the conduit means for transferring hydraulic medium from the reservoir to the cylinder to provide elevator up travel, a first return conduit between the cylinder and the reservoir for returning hydraulic medium to the reservoir to provide elevator down travel under the influence of gravity, a second return conduit between the cylinder and the pumping mechanism for returning hydraulic medium to the reservoir during elevator up travel, and a variable flow control valve operable through a continuous range in each of the return conduits for controlling the flow of the hydraulic medium through the return conduits and thus for controlling the flow of the hydraulic medium into and out of the cylinder.

2. In a hydraulic elevator system, in combination, a hydraulic cylinder, a reservoir containing a hydraulic medium, conduit means connecting the cylinder and the reservoir, pumping mechanism in the conduit means for transferring hydraulic medium from the reservoir to the cylinder to provide elevator up travel, a first return conduit between the cylinder and the reservoir for returning hydraulic medium to the reservoir to provide elevator down travel under the influence of gravity, a second return conduit between the cylinder and the pumping mechanism for returning hydraulic medium to the reservoir during elevator up travel, variable flow valve means in the return conduits for controlling the flow of the hydraulic medium through the return conduits and thus for controlling the flow of the hydraulic medium into and out of the cylinder, and means, isolated from the hydraulic medium, for causing the valve means to open and close slowly providing controlled acceleration and deceleration on up travel and on down travel.

3. In a hydraulic elevator system, in combination, a hydraulic cylinder, a reservoir containing a hydraulic medium, conduit means connecting the cylinder and the reservoir, pumping mechanism in the conduit means for transferring hydraulic medium from the reservoir to the cylinder to provide elevator up travel, a first return conduit between the cylinder and the reservoir for returning hydraulic medium to the reservoir to provide elevator down travel under the influence of gravity, a second return conduit between the cylinder and the pumping mechanism for returning hydraulic medium to the reservoir

during elevator up travel, valve means in the return conduits for controlling the flow of the hydraulic medium through the return conduits and thus for controlling the flow of the hydraulic medium into and out of the cylinder, the valve means providing an adjustable flow, and means sensitive to the pressure of the hydraulic medium for adjusting the valve means to vary valve range limits according to various loadings of the elevator, whereby uniform leveling and running speeds are provided.

4. In a hydraulic elevator system, in combination, a hydraulic cylinder, a reservoir containing a hydraulic medium, conduit means connecting the cylinder and the reservoir, pumping mechanism in the conduit means for transferring hydraulic medium in forward flow from the reservoir to the cylinder to provide elevator up travel, a first return conduit between the cylinder and the reservoir for returning hydraulic medium to the reservoir to provide elevator down travel under the influence of gravity, a stop valve in the first return conduit for preventing said return of hydraulic medium to the reservoir during elevator up travel, a second return conduit between the cylinder and the pumping mechanism for returning hydraulic medium to the reservoir during elevator up travel, means in the hydraulic circuit for preventing backward flow of hydraulic medium to the second return conduit, and a control valve in each of the return conduits for controlling the flow of the hydraulic medium through the return conduits and thus for controlling the flow of the hydraulic medium into and out of the cylinder.

5. In a hydraulic elevator system, in combination, a hydraulic cylinder, a reservoir containing a hydraulic medium, conduit means connecting the cylinder and the reservoir, pumping mechanism in the conduit means for transferring hydraulic medium in forward flow from the reservoir to the cylinder to provide elevator up travel, a first return conduit between the cylinder and the reservoir for returning hydraulic medium to the reservoir to provide elevator down travel under the influence of gravity, a stop valve in the first return conduit for preventing said return of hydraulic medium to the reservoir during elevator up travel, a second return conduit between the cylinder and the pumping mechanism for returning hydraulic medium to the reservoir during elevator up travel, means in the hydraulic circuit for preventing backward flow of hydraulic medium to the second return conduit, valve means in the return conduits for controlling the flow of the hydraulic medium through the return conduits and thus for controlling the flow of the hydraulic medium into and out of the cylinder, and means, isolated from the hydraulic medium, for retarding operation of the valve means to provide controlled acceleration and deceleration on up travel and on down travel.

6. In a hydraulic elevator system, in combination, a hydraulic cylinder, a reservoir containing a hydraulic medium, conduit means connecting the cylinder and the reservoir, pumping mechanism in the conduit means for transferring hydraulic medium in forward flow from the reservoir to the cylinder to provide elevator up travel, a first return conduit between the cylinder and the reservoir for returning hydraulic medium to the reservoir to provide elevator down travel under the influence of gravity, a stop valve in the first return conduit for preventing said return of hydraulic medium to the reservoir during elevator up travel, a second return conduit between the cylinder and the pumping mechanism for returning hydraulic medium to the reservoir during elevator up travel, means in the hydraulic circuit for preventing backward flow of hydraulic medium to the second return conduit, valve means in the return conduits for controlling the flow of the hydraulic medium through the return conduits and thus for controlling the flow of the hydraulic medium into and out of the cylinder, the valve means providing an adjustable flow, and means sensitive to the pressure of the hydraulic medium for adjusting the valve

means according to various loadings of the elevator, whereby uniform leveling and running speeds are provided.

7. In a control system for a hydraulic elevator having a hydraulic cylinder, in combination, variable flow valve means for controlling the flow of a hydraulic medium into and out of the cylinder, and means sensitive to the pressure of the hydraulic medium for controlling the degree of opening and of closing of the valve means to vary valve range limits according to various loadings of the elevator.

8. In a control system for a hydraulic elevator having a hydraulic cylinder, in combination, valve means for controlling the flow of a hydraulic medium into and out of the cylinder, the valve means operating within range limits, and diaphragm means sensitive to the pressure of the hydraulic medium for adjusting the valve means to vary the range limits according to various loadings of the elevator.

9. In a control system for a hydraulic elevator having a hydraulic cylinder, in combination, adjustable stop means defining adjustable limits, valve means operable within a range between the adjustable limits for controlling the flow of a hydraulic medium into and out of the cylinder, the degree of opening and of closing of the valve means and thus the range limits being adjustable by adjusting the stop means, and diaphragm means sensitive to the pressure of the hydraulic medium for adjusting the stop means for various elevator loadings.

10. In a control system for a hydraulic elevator having a hydraulic cylinder, in combination, variable flow valve means for controlling the flow of hydraulic medium into and out of the cylinder, and dashpot means, isolated from the hydraulic medium, operatively connected to the valve means for retarding the opening and the closing of the valve means to provide controlled acceleration and deceleration on up travel and on down travel.

11. In a control system for a hydraulic elevator having a hydraulic cylinder, in combination, an up control variable flow valve for controlling the flow of a hydraulic medium into the cylinder, a down control variable flow valve for controlling the flow of the hydraulic medium out of the cylinder, and a dashpot, isolated from the hydraulic medium, operatively connected to each of the valves for retarding its opening and closing to provide controlled acceleration and deceleration on up travel and on down travel.

12. In a hydraulic elevator system, in combination, a hydraulic cylinder, a reservoir containing a hydraulic medium, conduit means connecting the cylinder and the reservoir, pumping mechanism in the conduit means for transferring hydraulic medium from the reservoir to the cylinder to provide elevator up travel, a first return conduit between the cylinder and the reservoir for returning hydraulic medium to the reservoir to provide elevator down travel under the influence of gravity, a second return conduit between the cylinder and the pumping mechanism for returning hydraulic medium to the reservoir during elevator up travel, and a control valve in each of the return conduits for controlling the flow of the hydraulic medium through the return conduits and thus for controlling the flow of the hydraulic medium into and out of the cylinder, each of the control valves including a casing communicating with the respective return conduit, a sleeve stationarily mounted within the casing and having inlet ports for receiving the hydraulic medium under relatively high pressure from the casing and outlet ports for discharging the hydraulic medium to the reservoir at relatively low pressure and an insert which is slidably mounted within the sleeve for controlling the flow from the outlet ports.

13. In a hydraulic elevator system, in combination, a hydraulic cylinder, a reservoir containing a hydraulic medium, conduit means connecting the cylinder and the reservoir, pumping mechanism in the conduit means for

transferring hydraulic medium from the reservoir to the cylinder to provide elevator up travel, a first return conduit between the cylinder and the reservoir for returning hydraulic medium to the reservoir to provide elevator down travel under the influence of gravity, a second return conduit between the cylinder and the pumping mechanism for returning hydraulic medium to the reservoir during elevator up travel, and a control valve in each of the return conduits for controlling the flow of the hydraulic medium through the return conduits and thus for controlling the flow of the hydraulic medium into and out of the cylinder, each of the control valves including a casing communicating with the respective return conduit, a sleeve stationarily mounted within the casing and having inlet ports for receiving the hydraulic medium under relatively high pressure from the casing and outlet ports for discharging the hydraulic medium to the reservoir at relatively low pressure, an insert which is slidably mounted within the sleeve for controlling the flow from the outlet ports, and means tending to balance the forces on the insert even though it experiences a pressure drop adjacent the outlet ports.

14. In a hydraulic elevator system, in combination, a hydraulic cylinder, a reservoir containing a hydraulic medium, conduit means connecting the cylinder and the reservoir, pumping mechanism in the conduit means for transferring hydraulic medium in forward flow from the reservoir to the cylinder to provide elevator up travel, a first return conduit between the cylinder and the reservoir for returning hydraulic medium to the reservoir to provide elevator down travel under the influence of gravity, a stop valve in the first return conduit for preventing said return of hydraulic medium to the reservoir during elevator up travel, a second return conduit between the cylinder and the pumping mechanism for returning hydraulic medium to the reservoir during elevator up travel, means in the hydraulic circuit for preventing backward flow of hydraulic medium to the second return conduit, and a control valve in each of the return conduits for controlling the flow of the hydraulic medium through the return conduits and thus for controlling the flow of the hydraulic medium into and out of the cylinder, each of the control valves including a casing communicating with the respective return conduit, a sleeve stationarily mounted within the casing and having inlet ports for receiving the hydraulic medium under relatively high pressure from the casing and outlet ports for discharging the hydraulic medium to the reservoir at relatively low pressure and an insert which is slidably mounted within the sleeve for controlling the flow from the outlet ports.

15. In a hydraulic elevator system, in combination, a hydraulic cylinder, a reservoir containing a hydraulic medium, conduit means connecting the cylinder and the reservoir, pumping mechanism in the conduit means for transferring hydraulic medium in forward flow from the reservoir to the cylinder to provide elevator up travel, a first return conduit between the cylinder and the reservoir for returning hydraulic medium to the reservoir to provide elevator down travel under the influence of gravity, a stop valve in the first return conduit for preventing said return of hydraulic medium to the reservoir during elevator up travel, a second return conduit between the cylinder and the pumping mechanism for returning hydraulic medium to the reservoir during elevator up travel, means in the hydraulic circuit for preventing backward flow of hydraulic medium to the second return conduit, and a control valve in each of the return conduits for controlling the flow of the hydraulic medium through the return conduits and thus for controlling the flow of the hydraulic medium into and out of the cylinder, each of the control valves including a casing communicating with the respective return conduit, a sleeve stationarily mounted within the casing and having inlet ports for receiving the hydraulic medium under relatively high pressure from the casing and outlet ports

for discharging the hydraulic medium to the reservoir at relatively low pressure, an insert which is slidably mounted within the sleeve for controlling the flow from the outlet ports, and means tending to balance the forces on the insert even though it experiences a pressure drop adjacent the outlet ports.

16. A hydraulic elevator system comprising, in combination, load carrying means, a plunger operatively connected to the load carrying means, a hydraulic cylinder for the plunger, a reservoir containing a hydraulic medium, conduit means connecting the cylinder and the reservoir, pumping mechanism in the conduit means for transferring hydraulic medium from the reservoir to the cylinder to provide elevator up travel, means for causing operation of the pumping mechanism to raise the load carrying means, up control valve means operable at the start of the pumping mechanism to cause acceleration of the load carrying means and operable as the load carrying means nears a selected level to cause deceleration of the load carrying means to a leveling speed, means for stopping the pumping mechanism and thus the load carrying means when the load carrying means becomes level with the selected level, a return conduit located between the cylinder and the reservoir for returning hydraulic medium to the reservoir to provide elevator down travel under the influence of gravity, a stop valve in the return conduit which is closed during up travel, means for causing the opening of the stop valve to lower the load carrying means, a down control valve in the return conduit operable at the opening of the stop valve to cause acceleration of the load carrying means and operable as the load carrying means nears a selected level to cause deceleration of the load carrying means to a leveling speed, and means for closing the stop valve and thus for stopping the load carrying means when the load carrying means becomes level with the selected level.

17. A hydraulic elevator system according to claim 16 wherein the means for stopping the pumping mechanism and thus the load carrying means when the load carrying means becomes level with the selected level functions additionally to restart the pumping mechanism to raise the load carrying means at leveling speed should the stopped load carrying means settle below the selected level and again stops the pumping mechanism and thus the load carrying means when the load carrying means becomes level with the selected level.

18. A hydraulic elevator system according to claim 16 wherein delay means are provided to permit operation of the up control valve means to start before operation of the pumping mechanism begins on up travel.

19. A hydraulic elevator system according to claim 16 wherein the up control valve means includes a by-pass located between the cylinder and the pumping mechanism for returning hydraulic medium to the reservoir during up travel and an up control valve in the by-pass for controlling the flow of the hydraulic medium through the by-pass and thus for controlling the flow of the hydraulic medium into the cylinder.

20. A hydraulic elevator system according to claim 16 wherein the acceleration and deceleration provided by the up control valve means and by the down control valve is caused by dashpot means isolated from the hydraulic medium and operatively connected to the up control valve means and to the down control valve whereby they open and close slowly.

21. A hydraulic elevator system according to claim 16 wherein means are provided which are sensitive to the pressure of the hydraulic medium in the conduit means for controlling the degree of opening and of closing of the up control valve means and the down control valve according to various loadings of the load carrying means, whereby uniform leveling and running speeds for various loadings are obtained.

22. A hydraulic elevator system according to claim

19 wherein both of the control valves leak hydraulic medium to the reservoir even when such valves are closed.

23. A hydraulic elevator system according to claim 22 wherein each of the control valves provides an adjustable leakage to the reservoir.

24. A hydraulic elevator system according to claim 23 wherein diaphragm means are provided which are sensitive to the pressure of the hydraulic medium in the conduit means for adjusting the control valves automatically according to various loadings of the load carrying means.

25. A hydraulic elevator system comprising, in combination, load carrying means, a plunger operatively connected to the load carrying means, a hydraulic cylinder for the plunger, a reservoir containing a hydraulic medium, conduit means connecting the cylinder and the reservoir, pumping mechanism in the conduit means for transferring hydraulic medium from the reservoir to the cylinder to provide elevator up travel, means for causing operation of the pumping mechanism to raise the load carrying means, up control valve means for controlling the flow of the hydraulic medium into the cylinder operable at the start of the pumping mechanism to cause acceleration of the load carrying means and operable as the load carrying means nears a selected level to cause deceleration of the load carrying means to a leveling speed, means for stopping the pumping mechanism and thus the load carrying means when the load carrying means becomes level with the selected level, means for returning hydraulic medium to the reservoir to provide elevator down travel under the influence of gravity, down control valve means for controlling the flow of the hydraulic medium out of the cylinder operable at the start of the elevator down travel to cause acceleration of the load carrying means and operable as the load carrying means nears a selected level to cause deceleration of the load carrying means to a leveling speed, and means for stopping said return of hydraulic medium to the reservoir to stop the load carrying means when the load carrying means becomes level with the selected level.

26. A hydraulic elevator system according to claim 25 wherein the means for stopping the pumping mechanism and thus the load carrying means when the load carrying means becomes level with the selected level functions additionally to restart the pumping mechanism to raise the load carrying means at leveling speed should the stopped load carrying means settle below the selected level and again stops the pumping mechanism and thus the load carrying means when the load carrying means becomes level with the selected level.

27. A hydraulic elevator system according to claim 25 wherein delay means are provided to permit operation of the up control valve means to start before operation of the pumping mechanism begins on up travel.

28. A hydraulic elevator system according to claim 25 wherein the up control valve means includes a by-pass located between the cylinder and the pumping mechanism for returning hydraulic medium to the reservoir during up travel and an up control valve in the by-pass for controlling the flow of the hydraulic medium through the by-pass and thus for controlling the flow of the hydraulic medium into the cylinder.

29. A hydraulic elevator system according to claim 25

wherein the acceleration and deceleration provided by the control valve means is caused by damping means, isolated from the hydraulic medium, operatively connected to the valve means for slow operation of the valve means.

5 30. A hydraulic elevator system according to claim 25 wherein diaphragm means are provided which are sensitive to the pressure of the hydraulic medium in the conduit means for controlling the operation of the control valve means according to load upon the load carrying means, whereby uniform leveling and running speeds for various loadings are obtained.

10 31. A hydraulic elevator system according to claim 25 wherein both of the control valve means leak hydraulic medium to the reservoir even when such valve means are closed.

15 32. A hydraulic elevator system according to claim 31 wherein each of the control valve means provides an adjustable leakage to the reservoir.

20 33. A hydraulic elevator system according to claim 32 wherein compensator means are provided which are sensitive to the pressure of the hydraulic medium in the conduit means for adjusting the control valve means automatically according to various loadings of the load carrying means.

25 34. In a control system for a hydraulic elevator having a hydraulic cylinder which is supplied with a hydraulic medium, in combination, valve means including at least one valve for controlling the flow of the hydraulic medium into and out of the cylinder, a valve operating rod for opening and closing the valve and valve stop means carried by the rod, compensator stop means movably mounted adjacent the valve stop means, means for moving the valve operating rod until the valve stop means contacts the compensator stop means, and compensator means sensitive to the pressure of the hydraulic medium for positioning the compensator stop means according to such pressure and thereby controlling automatically the degree of opening and of closing of the valve according to various loadings of the elevator.

30 35. A control system for a hydraulic elevator according to claim 34 wherein a dashpot is connected to the means for moving the valve operating rod, whereby the valve is opened and closed slowly.

35 36. A control system for a hydraulic elevator according to claim 34 wherein the compensator means includes a diaphragm.

40 37. A control system for a hydraulic elevator according to claim 34 wherein the compensator means includes a diaphragm, a plunger that is operatively connected to the compensator stop and that is driven in one direction by the diaphragm, and a return spring for driving the plunger in a return direction.

45 38. A control system for a hydraulic elevator according to claim 37 wherein means are provided to adjustably prestress the return spring to vary the sensitivity of the diaphragm.
